UNITED STATES PATENT OFFICE.

JOSEPH D. COVEL, OF ORIN, WASHINGTON.

AERIAL TORPEDO.

1,300,930.

Specification of Letters Patent. Patented Apr. 15, 1919.

Application filed October 25, 1917. Serial No. 198,422.

To all whom it may concern:

Be it known that I, JOSEPH D. COVEL, a citizen of the United States, residing at Orin, in the county of Stevens and State of Washington, have invented certain new and useful Improvements in Aerial Torpedoes, of which the following is a specification.

This invention relates to improvements in destruction devices and it is the principal object of the invention to provide a torpedo capable of traveling through air into engagement with an objective located at a point distant from the place of launching; the torpedo exploding when striking the objective and completely demolishing the same and other objects thereabout.

Another and equally important object of the invention is to provide a torpedo having a plurality of air planes adapted to support the same while in flight and propellers for driving the torpedo through space into engagement with an objective.

Other improvements and novel details in the construction and arrangement of the various parts of the torpedo will be brought out more in detail in the description to follow which, for a clear understanding of the invention should be considered in connection with the accompanying drawings forming a part hereof, and wherein is disclosed, for the purpose of illustration, convenient and satisfactory embodiments of the invention.

In the drawings:—

Figure 1 is a side elevation of the improved torpedo,

Fig. 2 is an end elevation of the same,

Fig. 3 is a vertical transverse section therethrough, and,

Fig. 4 is a fragmentary detail in section of one end of the explosive containing body.

Having more particular reference to the drawings and in connection with which like reference characters will designate corresponding parts throughout the several views thereof, 1 represents the explosive containing body of the torpedo, the opposite ends of which are tapered as at 2 and have concentrically disposed openings formed therein, one of which is adapted to be closed by a screw threaded cap 3, while the other receives a portion of a firing pin 4 therethrough, the inner end of the firing pin being engageable with a fulminate whereby the explosive charge in the body 1 will be fired upon the actuation of the said pin 4.

As will be noted, the head of the firing pin projects for a distance beyond the forward end of the torpedo and as will be readily understood, permits the same to be first engaged with an objective in order that the device will be exploded.

Air planes 5 and 6 are arranged above and below the body 1 and are supported in spaced relation therefrom by truss rods 7, which rods as will be noted, have certain of their ends engaged with the marginal edges of the several planes while the remaining ends are secured in a suitable manner to the body 1.

Lateral planes 8 and 9 are hingedly connected as at 10 to the opposite sides of the body 1 and are engaged by the ends of trusses 11 having turn-buckles 12 interposed therein and their remaining ends connected to the upper and lower portions of the said sides of the body. Obviously, by adjusting the turn buckles 12 the positions of the lateral planes 8 and 9 may be varied and as a consequence, the torpedo may be directed into engagement with its objective by adjusting the lateral planes 8 and 9 prior to the launching thereof; it of course being understood in this particular connection, that the distance of the objective from the place of launching or the range is first ascertained.

To positively prevent undue flexing of the opposite sides of the upper and lower air planes 5 and 6, I connect vertical truss rods 13 to the side marginal edges thereof, thus, maintaining the same rigid during flight of the torpedo.

Propeller shafts 14 and 15 are journaled in suitable bearings upon the torpedo and extend longitudinally of the planes 5 and 6, it being noted that the shaft 14 is arranged adjacent the plane 5 while the shaft 15 is arranged adjacent the plane 6. Propellers 16 are mounted upon the opposite extremities of the shafts 14 and 15 and are arranged beyond the adjacent ends of the air plane construction.

To permit the transmission of rotary motion to the propellers 16, a sprocket wheel 17 is fixedly mounted on the shaft 14 and is engaged by a sprocket chain 18 which in turn is arranged about a second sprocket wheel mounted on the power shaft of an internal combustion engine 19 or other suitable prime mover. The engine 19 is supported upon a bed 20 arranged upon the top

of the charge containing body 1. A second sprocket wheel 21 is mounted on the shaft 14 in proximity to one end thereof and receives a sprocket chain 22 thereabout, which sprocket chain is passed about a sprocket wheel 23 mounted on the propeller shaft 15. Thus, upon operation of the engine 19, rotary motion will be transmitted from the power shaft thereof to the various propellers 16 and as a consequence, the torpedo will be driven through space at a high velocity.

In order that the path of travel of the torpedo may be followed by persons launching the same, I mount a searchlight 24 upon the forward portion of the charge containing body 1, supplying the same with the necessary energy from a dynamo 25 also mounted on the engine bed 20 and connected to the power shaft of the said engine. Thus, the course taken by the torpedo subsequent to its launching may be readily observed.

The body 1 may be filled with an explosive charge by way of the opened end thereof and subsequent to the filling operation may be closed by turning the screw threaded cap 8 over the opened end.

Manifestly, the construction shown is capable of considerable modification and such modification as is within the scope of my claims, I consider within the spirit of my invention.

I claim:

1. An aerial torpedo, including an explosive containing body, planes arranged above and below said body in spaced relation thereto, laterally extending longitudinal supplemental planes hingedly engaged with the body on the opposite sides thereof intermediate the top and bottom portions of the body, means for adjusting said lateral planes, and propelling means arranged on the torpedo.

2. An aerial torpedo, including an explosive containing body, planes arranged above and below said body in spaced relation thereto, truss means for securely connecting said planes to the body, laterally extending longitudinal supplemental planes hingedly engaged with the opposite sides of the body intermediate the top and bottom portions thereof, means for adjusting the positions of said planes, and propelling means arranged on the torpedo.

3. An aerial torpedo, including an explosive containing body, planes arranged above and below said body in spaced relation thereto, truss means for securing the planes to the body, laterally extending longitudinal supplemental planes hingedly connected to the opposite sides of said body intermediate the top and bottom portions thereof, truss means for adjusting the positions of said lateral planes, propellers mounted in bearings at points in proximity to the forward and rear extremities of the torpedo, and an engine connected to said propellers.

In testimony whereof, I affix my signature hereto.

JOSEPH D. COVEL.
